ATTORNEY:

UNITED STATES PATENT OFFICE.

JOHN VICTOR ALLEN, OF PROVIDENCE, RHODE ISLAND, ASSIGNOR OF ONE-HALF TO HOWARD BRONSDON WEEKS, OF PROVIDENCE, RHODE ISLAND.

NON-TANGLING DEVICE FOR FLAGS.

1,277,347.

Specification of Letters Patent.

Patented Sept. 3, 1918.

Application filed November 22, 1917. Serial No. 203,368.

To all whom it may concern:

Be it known that I, JOHN VICTOR ALLEN, a citizen of the United States, residing at Providence, in the county of Providence and 5 State of Rhode Island, have invented a new and useful Improvement in Non-Tangling Devices for Flags, of which the following is a specification.

With flagpoles placed at a slant or in a 10 horizontal position, it is desirable that the flag should hang downward free of the pole, so as to insure its proper display. When held in place by securing the flag to the halyards only, the flag is free to be whipped, 15 wrapped or tangled by the wind around the flagpole, thereby giving an unsightly appearance and causing injury to the flag.

My invention relates to a non-tangling device adapted to be attached to the edge of 20 a flag which is suspended from a slanting or horizontal flagpole; the object of the device being to prevent the flag from becoming tangled or wrapped about the pole, and to cause the flag to hang downwardly in a manner that will insure its display without unduly hampering its freedom of motion in the wind.

The object of my invention is to improve 30 the construction of a non-tangling device for flags, whereby the device is formed of wire with a light coiled spring flag clamp at the upper end and a heavy coiled spring flag clamp at the lower end for weight; the device being secured to the flag by forcing the 35 edge of the flag into and between the spring coils of the flag clamps, also forming, on the larger and heavier sizes, a hook-shaped upper end which hooks into a grommet in the flag, thereby more positively securing the 40 heavier device to the flag.

Further objects of my invention are to simplify the construction and reduce the cost of manufacturing such non-tangling devices for flags.

45 My invention consists in the peculiar and novel construction of a non-tangling device for flags, said device having details of construction, as will be more fully set forth hereinafter and claimed.

50 Figure 1 is a side view of a flagpole from which is suspended a flag provided with my improved non-tangling device.

Fig. 2 is an enlarged side view of the non-tangling device, as shown in Fig. 1, and having the hook-shaped upper end as used

on the larger and heavier devices, for the larger size flags.

Fig. 3 is an edge view of Fig. 2.

Fig. 4 is a side view of a lighter and smaller size of the device as used on the 60 smaller size flags, the light weight of which does not require the hook-shaped upper end for securing it to the grommet, and

Fig. 5 is an edge view of Fig. 4.

In the drawing, 6 indicates a flagpole, 7 65 the halyards, 8 a flag having the usual grommets 9.9, and 10 my improved non-tangling device. The ends of the halyards 7 are secured to the grommets 9.9 of the flag 8 in the usual way, thereby suspending the flag from 70 the pole, as shown in Fig. 1.

My improved non-tangling device 10 is preferably constructed in various sizes for different sizes of flags. For the larger sizes of flags it is constructed of heavy wire 75 shaped to have a straight body portion 11, a hook-shaped upper end 12 bent at an angle to the body portion 11, a light coiled spring flag clamp 13 adjacent the upper end and a comparatively heavy coiled spring 80 flag clamp 14 on its lower end for weight as shown in Figs. 2 and 3. For the smaller sizes of flags, the device is made of light wire and the hook-shaped upper end 12 is dispensed with, as shown in Figs. 4 and 5, as 85 being unnecessary. In the larger sizes the coiled spring flag clamps 13 and 14 are made oval shaped as shown in Fig. 2, so as to give a deeper and stronger grip on the flag, and in all of the various sizes the lower coiled 90 spring flag clamps are made heavier, so as to form a weighted lower end, by increasing the number of the coils, as shown in Figs. 3 and 5.

The device is easily and quickly attached 95 to a flag by hooking the hook-shaped upper end 12 through the outer grommet 9 of the flag, and then forcing the edge of the flag between the coils of the spring flag clamps 13 and 14, as shown in Fig. 1, and 100 as easily and quickly detached by reversing these operations. The device is extremely simple in construction, it can be manufactured at a low cost and sold at a correspondingly low price and when in use will accomplish all that more complicated and much higher priced devices for the same purpose, 105 will do.

I am aware of other devices for the same purpose, such as shown in United States 110

Patents No. 982,645, No. 1,151,658, and No. 1,195,224, but I am not aware of any other device for this purpose which is constructed of wire with coiled spring wire flag clamps, by which the device is detachably secured to the flag and also having a hook-shaped upper end by which the device is more positively secured, by hooking the hook-shaped upper end through a grommet in the flag.

13 Having thus described my invention I claim as new:

1. A non-tangling device for flags, consisting of an elongated body portion having a hook-shaped upper end, a closed coiled spring flag clamp adjacent the upper end and a closed coiled spring flag clamp on its lower end, formed integral of wire, said closed coiled spring flag clamps holding the edge of a flag between the coils under spring 20 tension, as described.

2. In a device of the nature specified, an elongated member formed of wire and having a straight body portion on each end of which is a tightly closed coiled spring flag 25 clamp, said closed coiled spring flag clamps being adapted to close under spring tension on each side of a flag, at its edge, for the purpose as described.

3. In a device of the nature specified, an elongated member formed of wire and having a straight body portion, a hook-shaped upper end bent at an angle to the body portion, a tightly closed coiled spring flag clamp formed of two tightly closed coils adjacent the upper end and extending sidewise from the body portion and a coiled spring flag clamp formed of four tightly closed coils at the lower end of the body portion for weight and extending sidewise from the body portion, all formed integral, said closed coiled 40 spring flag clamp being adapted to close under spring tension, at each side of a flag, at its edge, for the purpose as described.

4. A non-tangling device for flags, consisting of an elongated body portion adapted to extend along the edge of a flag, and closed spring clamping means on the body portion adapted to detachably secure the device to the edge of a flag under spring tension, all formed integral, said closed spring 50 clamping means being adapted to close under spring tension, on each side of a flag, at its edge, for the purpose as described.

In testimony whereof I have signed my name to this specification.

JOHN VICTOR ALLEN.
